DESIGN FOR A DISPENSING HEAD FOR A
BUTANE SYSTEM

Starr L. Pitzer, Dallas, Tex., assignor to Continental L-P Products Company, Dallas, Tex., a partnership consisting of Starr L. Pitzer and Kemp Eldon

Application August 29, 1946, Serial No. 132,947

Term of patent 7 years

(Cl. D91—1)

To all whom it may concern:

Be it known that I, Starr L. Pitzer, a citizen of the United States of America, residing at Dallas, in the county of Dallas and State of Texas, have invented a new, original, and ornamental Design for a Dispensing Head for a Butane System, of which the following is a specification, reference being had to the accompanying drawings, forming a part thereof.

Fig. 1 is a perspective view of a dispensing head for a butane system, shown my new design,

Fig. 2 is a top plan view of the head,

Fig. 3 is an underside plan view of the head,

Fig. 4 is a side view taken from the rear of Fig. 1,

Fig. 5 is a side view taken from the front of Fig. 1,

Fig. 6 is a view taken from the left side of Fig. 1, and

Fig. 7 is a view taken from the right side of Fig. 1.

I claim:

The ornamental design for a dispensing head for a butane system, as shown.

STARR L. PITZER.
